UNITED STATES PATENT OFFICE.

ALBEN E. LUNDELL, OF NEW YORK, N. Y., ASSIGNEE TO WESTERN ELECTRIC COMPANY,
INCORPORATED, OF NEW YORK, N. Y., A CORPORATION OF NEW YORK.

AUTOMATIC TELEPHONE SYSTEM.

1,232,582.

Specification of Letters Patent. Patented July 10, 1917.

Application filed January 14, 1916. Serial No. 72,147.

To all whom it may concern:

Be it known that I, ALBEN E. LUNDELL, a citizen of the United States, residing at New York, in the county of Bronx and State of New York, have invented certain new and useful Improvements in Automatic Telephone Systems, of which the following is a full, clear, concise, and exact description.

This invention relates to automatic telephone systems in which the connection between calling and called lines is established wholly or in part by means of mechanically operated switching devices, and particularly to systems of the above character in which such mechanical switching devices are controlled in their movement by means of an operator's controlling mechanism or sending device at the central office.

The principal object of this invention resides in the provision in a telephone system, of the above described character in which switches having a plurality of normally retracted brushes and magnets for governing the release of a desired brush set, are employed, of circuits for said magnets controlled directly at the operator's sending mechanism.

Other features which are incident to the one just mentioned will appear as the description of the invention progresses.

In the drawings, Figures 1 and 2, with Fig. 1 at the top, diagrammatically indicate the apparatus and portions of the circuits employed in a telephone system embodying the present invention.

The mechanism or mechanical structures indicated on the drawings form no part of the present invention and will, therefore, be only briefly described.

In the drawings, a plurality of sequence switches are indicated. These sequence switches may be similar in structure to that shown in patent to Reynolds & Baldwin No. 1,127,808 and similar in operation and function to the corresponding sequence switches shown in patent to McBerty No. 1,125,579.

Two sequence switch structures are shown in Fig. 1. Sequence switch 200 at the upper left corner is the operator's listening-in sequence switch, and operates to connect the operator's listening set to a selected card circuit in a manner similar to the sequence switch of Fig. 6 of the McBerty patent. Sequence switch 100, near the middle of Fig.

1 has for its purpose the control of the circuits of the selector switch shown at the right in Fig. 1.

Sequence switch 300, which appears near the middle of Fig. 2, controls the circuits of the sender cord finder indicated at the left in Fig. 2 by means of which the operator's sender is joined to a selected cord circuit, and sequence switch 400 controls the operation of the operator's sending device. The sequence switch structures 500 and 600, which appear at the right in Fig. 2, are two of the call registering devices which take up the designation of a wanted line and control the operation of the sending device in accordance therewith. Register 500 we 70 will term the class of service register and register 600 will be referred to as the district brush register. Register devices of the same general character are shown in Fig. 3 of the above noted McBerty patent. Each 75 of the sequence switches is provided with a master contact. In each instance the master contact of a sequence switch is indicated on the drawings immediately above its power magnet and is indicated by a reference character ending in 01, the hundreds digit of the reference character being the same as that of the sequence switch it controls. These master contacts are open only at the sequence switch positions indicated 80 by the reference characters adjacent thereto. These characters therefore indicate the only positions at which the sequence switches can stop. All the other sequence switch contacts are open at all positions except those 85 indicated by the reference characters adjacent thereto. The contacts governed by each of the several sequence switches are separated from those governed by the others 90 by dotted lines and the confines of the sheets of the drawings and each sequence switch contact is indicated on the drawings by a reference character, the hundreds digit of which is the same as the hundreds digit of the sequence switch governing it.

The selector switch 102, shown at the right in Fig. 1 of the drawing, may be similar in structure and operation to that disclosed in an application to James L. McQuarrie, Serial No. 32,849, filed June 8, 1915. This switch is provided with a plurality of sets 103 of multiply connected brushes. Each set of brushes is provided

with a controlling device 104 which normally maintains the brushes of the set in retracted or inoperative position.

It will be understood that a group of 5 these selector switches are provided, and that the brush supporting shafts of the several switches are arranged substantially parallel to each other and in the same plane. Extending parallel to said shafts and adjacent to, but just below, the corresponding brush sets of each of the switches, is a brush tripping spindle 105 which is provided with a plurality of yokes 106, one for each switch in the group; and upon rotation of any 15 spindle 105 by its operating or trip magnet 117, the yokes 106 thereon are placed in the path of the controlling members 104, respectively, of all switches which are then in their normal positions. Then, upon the beginning 20 of the upward movement of a selected switch, the brush set at the level of the actuated trip spindle 105 will be released so as to engage the stationary terminals in the section of the contact bank over which it passes.

Adjacent to the lower end of the brush supporting shaft is a pair of constantly driven power drums which rotate in opposite directions. The elevating bar is arranged 30 to be forced into operative engagement with one or the other of said drums by the up-drive clutch magnet 107 or the down-drive clutch magnet 108 respectively, as shown in the McQuarrie application.

The line finder switch 302 at the left in Fig. 2, may be of the same general character as the selector switch 102, except it is provided with but one set of brushes, and no means are provided for normally holding 40 the brushes in inoperative position.

With this brief description of the apparatus employed, it is believed that the invention will be readily understood from a description of the manner in which the apparatus is employed in establishing a connection.

Assuming now that the subscriber at 109 removes his receiver from the hook, a circuit will be completed through the line relay 110, which, in attracting its armature, will cause the line lamp 111 to glow. The operator, seeing lamp 111 lighted, will insert the plug 112 in the jack of the calling line, completing a connection from battery, through the cut-off relay 113, sleeve contacts of the jack and plug and the cord relay 114 to ground. Both relays will operate. Relay 113 will interrupt the circuit for relay 110, and relay 114 will complete a circuit from ground through its armature and front contact, sequence switch contact 202 (1) and motor magnet of sequence switch 200 to battery and ground. This will cause the sequence switch 200 to be moved out of position 60 1 and into position 7 under the control

of its master contact 201. In position 7, the operator's set (not shown) will be connected to the selected cord circuit through contacts 203' and 204' (7) in a manner clearly disclosed in the said McBerty patent. When sequence switch 200 reached position 2, a circuit was closed from grounded battery through the motor magnet of the connecting circuit sequence switch 100, contact 203 (2 to 7), and contact 115 (1) to ground. Sequence switch 100 thereupon moves to position 2 under the control of its master contact 101.

In position 7 of the listening sequence switch, a circuit is completed from battery through relay 303, (Fig. 2), lower and upper sequence switch contacts 304 (1), conductor 305, contact 204 (7), and upper contact 115 (2) to ground. Relay 303 is energized and completes a circuit from battery through the motor magnet of sequence switch 300, sequence switch contact 306 (1), and the front contact and armature of relay 303. Sequence switch 300 thereupon moves to position 2. In moving to position 2 the original energizing path for relay 303 is interrupted at upper contact 304, but a substitute path to ground is provided through the lower left contact 304 and the back contact and right armature of relay 311. A circuit is now completed from battery through the up-drive clutch magnet 307 of the cord finder switch 302, sequence switch contacts 308 (2) and front contact and armature of relay 303 to ground, and the cord finder switch 302 starts to move upward. With sequence switch 100 in position 2 and the sequence switch 200 in position 7, a circuit was completed from ground (middle Fig. 1), through upper sequence switch contact 115 (2), upper sequence switch contact 204 (7), to the test terminal 309 of the cord finder switch, which represents the selected connecting circuit. Now, when in the upward movement of the switch 302, the contact 309 is engaged by the finder test brush, the circuit just traced will be extended through sequence switch contact 310 (2), and test relay 311 to battery and ground. Relay 311 will attract its armatures, breaking at its right armature and back contact the previously described holding circuit for the relay 303, which will retract its armature and open at its front contact the circuit for the up-drive clutch magnet 307 and will close at its back contact a circuit for the motor magnet of sequence switch 300 through sequence switch contact 306 (2), driving the cord finder sequence switch into position 3.

The operator's listening set being connected to the line of the calling subscriber through the contacts 203', 204' (7) of the listening switch 200, she converses with the calling subscriber and obtains the designa- 125 130

tion of the wanted line in the usual manner. On obtaining the desired information, the operator depresses the keys, in accordance with the number of the wanted subscriber.

5 Only one key 602 is shown in the drawings. This is one of the keys of the district brush selecting group. It will be understood, of course, that other sets of keys, as office, thousands, hundreds, tens and units sets will 10 be provided in the usual manner.

The registers 500 and 600 are both controlled by the district brush selecting keys. Upon depressing the district brush selecting key 602, a circuit is completed from battery 15 through left sequence switch contact 315 (3) (middle of Fig. 2), the motor magnet of class-of-service register 500, back contact and right armature of register test relay 503, to ground, through the right contact 20 of key 602. Another circuit is simultaneously closed from battery through right contact 315, motor magnet of district brush register 600, back contact and armature of relay 603, to ground, through the right contact 25 tact of key 602. Both the register motor magnets are energized and the registers start rotating.

When the district brush register 600 reaches position 5, a circuit will be completed from battery through relay 316, test or cutoff relay 603, register contact 604 (5), to ground through the key. The relay 603 attracts its armature and opens the circuit for the motor magnet of register 600, causing 35 the register to stop in position 5, in which position all the contacts, adjacent to which appear the numeral 5, are closed. The register 500 is also rotating, and when it reaches position 9, a circuit will be completed from battery through relay 316, relay 503, register contact 504 (9), and the left contact of key 602 to ground. Relay 503 will be energized and open the circuit for the motor magnet of register 500, stopping 40 said register in position 9. Relays 503 and 603 being now both energized, a circuit is completed from battery through the motor magnet of sequence switch 300, sequence switch contact 317 (3), front contact and 45 left armature of relay 503, front contact and armature of relay 603 to ground through the right contact of key 602, thus causing the sequence switch 300 to move into position 4. Sequence switch 300 will be moved 50 out of position 4 by means of a circuit closed through sequence switch contact 317 (4) and contacts of the trip relay and key of the district group register, in a manner similar to that in which it was moved out of position 55 3 by means of contacts controlled by key 602.

In moving out of position 4, the sequence switch 300 is moved to position 6 by its master contact 301. When the cord finder sequence switch 300 moved to position 4, a 60 circuit was completed from battery through

uppermost trip magnet 117, district brush register contact 605 (5), class of service register contact 505 (2 to 9), sequence switch contact 403 (1) and sequence switch contact 318 (4 to 6) to ground. The magnet 117 70 will be energized, thus insuring that the uppermost set of brushes on the selector switch will be released when the switch begins its upward movement. It will be noted that each of the selector switch trip magnets has 75 a circuit which may be closed at one of the contacts of the district brush register at some one of its five positions.

The connecting circuit sequence switch 100 being now in position 2, the cord finder sequence switch 300 in position 6, and the sender sequence switch 400 in position 2, a circuit will extend from battery through relay 120, both lower sequence switch contacts 121 (2), the left contact and brush of 80 switch 302, armature and back contact of stop relay 404, the winding of stepping relay 405, sequence switch contact 406 (2), and contact 318 (3 to 8) to ground. This circuit, which is the impulse or fundamental circuit, 85 causes the energization of relay 120, which completes a circuit from battery through the motor magnet of sequence switch 100, sequence switch contact 122 (2), and the front contact and left armature of said relay to ground, causing sequence switch 100 90 to move to position 3.

As switch 100 moves to position 3, the circuit for relay 120 is opened at the lower left contact 121, but the relay remains locked 100 up over the fundamental circuit through its right armature and upper left contact 121. A circuit is now completed from battery through the up-drive clutch magnet 107 of selector switch 102, sequence switch contact 105 123 (3), and the front contact and left armature of relay 120 to ground. This causes the selector switch to move upward. In its initial movement, the upper brush controlling device 104 is engaged by the corresponding trip yoke 106 on the shaft 105, causing the release of the upper set of brushes.

It is to be understood that each set of 115 brushes of the selector switch 102 is arranged to traverse 100 sets of terminal contacts of trunks. These trunks will be divided into groups of such size as will best satisfy the traffic requirements. In the present description, we will assume that the desired line will be reached through one of the 120 trunks in the lowermost group arranged to be seized by the upper set of brushes. The district group register will therefore be in position 1, thus closing a circuit to the last pair α and α' of counting relays of the 125 sender, in a manner similar to that disclosed in applicant's copending application Serial No. 786,165, filed August 22, 1913. Therefore, when the fundamental or impulse circuit was closed, as above described, relay α 130

was energized by a circuit from battery through said relay, district group register contact 1, contact 407 (2), and armature and contact of stepping relay 405 to ground.

- 5 Relay o , in attracting its armature, completes a circuit for its companion counting relay o' and also for the cutoff or stop relay 404 through upper left contact 408 (2). These latter two relays are, however, at this 70 time short-circuited by the branch to ground through the armature and contact of relay 405.

As the switch moves upward, the stepping relay 405 is shunted by a circuit extending 15 from the upper right contact 121 (3) through the first conducting segment of commutator 124 and the grounded brush 125. The segments of commutator 124 are so positioned that one of them will be engaged by brush 125 as the switch brushes approach the bottom of a group of trunks. These interruptions or short circuits of the relay 405 measure or count the number of groups passed over by the switch brushes, 25 relay 405 being deenergized once for each group passed over.

The dotted lines extending to the left from upper and lower sequence switch contacts 408 indicate the conductors arranged to form 30 portions of the locking circuits for the other counting relays.

In the case assumed, when relay 405 retracts its armature the first time, due to the short circuit through the lowermost segment 35 of the interrupter 124, it will remove the short-circuit from relays o' and 404 and they will be energized in a circuit in series with relay o .

Relay 404, being energized, the energizing circuit extending through relay 120 will be interrupted as soon as the brush 125 passes from engagement with the contact segment on the interrupter 124. Relay 120 will then retract its armatures, completing 45 a circuit from battery through the motor magnet of sequence switch 100, contact 122 (3), and back contact and left armature of relay 120 to ground. When the left armature of relay 120 was retracted, it interrupted the circuit for the motor magnet 107, causing the selector switch to pause at the 50 beginning of the selected group. An instant later, the circuit previously traced for this clutch magnet is opened at sequence switch contact 123 (3). Trunk selection or hunting in the selected group may take place in the usual and well-known manner.

With the energization of the last counting relay o' , a circuit was completed from battery through the motor magnet of sequence switch 400, contact and armature of said relay, and upper right sequence switch contact 408 (2) to ground. Sequence switch 400 thereupon moves out of position 2 and 65 into position 4 under the control of its mas-

ter contact 401. In moving out of position 2, the holding circuits for all the counting relays which have been operated and locked up, as well as relay 404, are interrupted at sequence switch contact 408. These relays 70 thereupon fall off, and when the sequence switch 400 reaches position 4, a locking circuit is provided which will be effective upon the next energization of the counting relays.

At the end of district group selection, the connecting circuit sequence switch 100 will move out of position 3, and during the subsequent operations in controlling trunk hunting in the selected group and the movement of the following switches it will be 75 moved to position 11. We left sequence switch 300 in position 6, and when sequence switch 400 moved to position 3, a circuit was established from battery through the motor magnet of switch 300, contact 317 (6) and 80 contact 409 (3). This will cause switch 300 to move out of position 6. In position 7, it closes a circuit at contact 312 for the key release magnet 506, thus causing key 602 to return to its normal position. This contact may also close circuits for the release 85 magnets of all other key sets. During the subsequent sending operations, the sequence switch 300 will be moved through its successive positions, coming to rest at the end 90 of the sending operation in position 15. Likewise the sequence switch 400 will be moved through its positions 4, 6, 8, 10, 12 and will have been moved to position 16 at the end of the sending operation.

During the selecting operation at the switches beyond the selector switch 102, the fundamental circuit will be extended to the subsequent switches through sequence switch contact 126 and one of the brushes of the selector switch 102, in a manner which is well understood.

It was above described how sequence switch 100 was moved to position 11 during the establishment of a connection. Now 110 when sequence switch 400 moves to position 16 after the last operation of the operator's controlling device a circuit was established from battery through the motor magnet of sequence switch 100, contact 122 (11), the 115 right contact and brush of switch 302 and sequence switch contact 411 (16) to ground. Sequence switch 100 will thereupon be moved out of position 11 into position 12. We will assume that sequence switch 100 is in position 12 while the called subscriber is being rung, and, that upon response of the called subscriber, it moves to position 16; the talking circuit will now be completed at contacts 127 and 128 (16).

It will be recalled that relay 311 was locked up by a circuit extending through contact 310 (2 to 16), its left contact and armature, the second-from-the-left brush and contact of switch 302, and sequence switch 115 125 130

(2 to 11) to ground. Now, when the sequence switch 100 moves out of position 11 at the end of the sending operation, the circuit for relay 311 will be interrupted at contact 115, and it will retract its armatures, completing a circuit from battery through the motor magnet of sequence switch 300, contact 319, (15), and the back contact and right armature of relay 311 to ground. The sequence switch 300 will thereupon move to position 17, when a circuit will be completed from battery through the motor magnet of sequence switch 400, contact 410 (10), sequence switch contact 319 (17), and back contact and right armature of relay 311 to ground. Sequence switch 400 thereupon moves out of position 16 and back to normal or position 1. A circuit is now completed from battery through the release and down-drive clutch magnet 320 of switch 302, sequence switch contact 410 (1), sequence switch contact 319 (17), and back contact and right armature of test relay 311 to ground. The sender cord finder thereupon returns to its normal position. As it approaches normal, the off-normal contact 321 is closed, completing a circuit from battery through the clutch magnet of sequence switch 300, sequence switch contact 306 (17), and the off-normal contact 321 to ground, thus driving the sequence switch 300 back to its normal position.

The registering devices employed have no normal position and remain in the position in which they were last used until the operator employs them in establishing another call.

When the connection is completed, the operator will remove her set from the cord circuit by causing her sequence switch 200 to move out of position 7. This may be accomplished by depressing the listening-out key 205 which will cause switch 200 to move to position 11. In practice, however, it will be brought about automatically, as in applicant's co-pending application above referred to.

Upon the termination of the conversation, when the subscribers replace their receivers upon the hooks, the supervisory disconnect signals (not shown) will be displayed in the usual manner. The operator, observing the disconnect signals, will remove the plug 112 from the jack of the calling line, causing the deenergization of relay 114. Relay 114, in retracting its armature, completes a circuit from battery through the motor magnet of switch 200, contact 206 (11) and the back contact and armature of relay 114 to ground. Sequence switch 200 thereupon moves to position 1, thus closing a circuit from battery through the motor magnet of sequence switch 100, sequence switch contact 130 (16) sequence switch contact 206 (1), and the back contact and armature of

relay 114 to ground. This will move the sequence switch 100 out of position 16, and it will go to position 18 under the control of its master contact 101. In position 18, a circuit is completed from battery through the release and down-drive clutch magnet 108 and sequence switch contact 131 (18) to ground. This will retract the holding pawl, and cause the return to normal of the selector switch 102. As the switch approaches its normal position, the right commutator brush will engage the conducting segment 132, completing a circuit from ground through said brush and contact, sequence switch contact 130 (18), and the motor magnet of sequence switch 100 to battery and ground. Sequence switch 100 will thereupon move out of position 18 and back to position 1 or normal.

The return of the switches beyond the switch 102 will take place in the usual and well understood manner.

Multiple brush selector switches, in which the particular brush selected was determined by a sending operation in which impulses were transmitted from the selector switch, in a manner similar to that for group selection, employ an interval of time in accomplishing this selection which is saved by the present invention, as the group selection may take place immediately upon the depression of the keys and the operation of the register device, the trip magnet 117, being energized immediately upon registration taking place, so that the necessary brush will be tripped upon the beginning of the upward travel of the selector switch.

In addition to this time saving element of the present invention, it has the further advantage of being absolutely positive in operation.

What is claimed is:

1. In a telephone system, telephone lines, means including a selector switch for establishing a connection from one of said lines to another, a plurality of normally inactive brush sets on said switch, an operator's sending device for controlling the operation of the switches used in establishing said connection, magnets, one for each brush set of said selector switch for controlling the release of the brushes thereof, circuits for said magnets, and contacts at said sending device for selectively closing said circuits.

2. In a telephone system, telephone lines, means including a selector switch for establishing a connection from one of said lines to another, a plurality of normally inactive brush sets on said selector switch, magnets, one for each brush set for controlling the activity thereof, an operator's sending device including keys and registers for recording the designation of a wanted line, circuits for said magnets, and contacts on said registers for selectively closing said circuits.

3. In a telephone system, telephone lines, means including any one of a group of selector switches for establishing a connection from one of said lines to another, a plurality of normally inactive brush sets on each of said switches, magnets, each being arranged to control the activity of the corresponding brush set on any of said switches, an operator's sending device for recording the designation of wanted lines, circuits for said magnets respectively, and contacts on said sending device for selectively closing said circuits to cause the release of a brush set in accordance with the designation of the wanted line.
4. In a telephone system, telephone lines, means including any one of a group of selector switches for establishing a connection from one of said lines to another, a plurality of normally inactive brush sets on each of said switches, magnets, each being arranged to cause the release of any of the corresponding brush sets on any of said switches, an operator's sending device including keys and registers for recording the designation of wanted lines, circuits for said magnets, and contacts on said registers for selectively closing said circuits.
5. In a telephone system, a telephone line, means for extending said line including a multiple brush selector switch, a central operator's sending device, means normally holding the brushes of said switch inactive, magnets, one for each brush set for releasing the brushes thereof, circuits for said magnets, and contacts at said sending device at which said circuits may be completed to release a desired brush set of said selector switch.
6. In a telephone system, telephone lines, means including any one of a group of selector switches for extending said lines, a plurality of multiply connected brush sets on each of said selector switches, means normally holding the brushes of said switches in inoperative position, release magnets and trip devices operated thereby, each device being arranged to release the corresponding brushes of any of said switches, a central operator's sending device including keys and registers, circuits for said magnets, and contacts on said registers for selectively closing said circuits.
7. In a telephone system, telephone lines, means including a selector switch for establishing a connection from one of said lines to another, a plurality of normally inactive brush sets on said switch, an operator's sending device including a key set and a pair of registers controlled thereby for recording the designation of a wanted line, magnets, one for each of said brush sets for controlling the release thereof, and circuits for said magnets respectively selectively closed through series contacts of said registers.
8. In a telephone system, telephone lines, means including any one of a group of selector switches for establishing a connection from one of said lines to another, a plurality of normally inactive brushes on each of said switches, release magnets each being arranged to render active the corresponding brush set of any of said switches, an operator's sending device including a key set and a pair of registers arranged to respond to the operation of any one of the keys in said set, and circuits for said magnets respectively closed at series contacts of both of said registers.
9. In a telephone system, telephone lines, means including any one of a group of selector switches for establishing a connection from one of said lines to another, a plurality of normally inactive brush sets on each of said switches, brush-tripping devices, each being arranged to control the activity of the corresponding brush sets of all of said switches, operating magnets for said tripping devices respectively, an operator's sending device for recording the designation of wanted lines, circuits for said magnets respectively, and contacts on said sending device for selectively closing said circuits to cause the release of a brush set in accordance with the designation of the wanted line.
10. In a telephone system, telephone lines, means including any one of a group of selector switches for establishing a connection from one of said lines to another, a plurality of normally inactive brush sets on each of said switches, brush-tipping devices common to said switches, each being arranged to control the release of the corresponding brush sets on all of said switches, operating magnets for said devices respectively, an operator's sending device including keys and registers for recording the designation of wanted lines, circuits for said magnets, and contacts on said registers for selectively closing said circuits.
11. In a telephone system, telephone lines, means for extending said lines including a multiple brush selector switch, a central operator's sending device, including a set of keys and a register controlled thereby, means normally holding the brushes of said switch inactive, magnets for said brush sets respectively for controlling the operation of said holding means, circuits for said magnets, and contacts at said register at which said circuits may be completed to release a desired brush set of said selector switch.
12. In a telephone system, telephone lines, means including any one of a group of selector switches for extending said lines, a plurality of multiply connected brush sets on each of said selector switches, means normally holding the brushes of said switches in inoperative position, brush-tripping devices common to said switches, operating

magnets for said tripping devices respectively each being arranged to control the release of the corresponding brushes of any of said switches, a central operator's sending device including keys and registers, circuits for said magnets, and contacts on said registers for selectively closing said circuits.

13. In a telephone system, telephone lines, means including any one of a group of selector switches for establishing a connection from one of said lines to another, a plurality of normally inactive brushes on each of said switches, brush-tripping devices common to said switches, operating magnets

for said tripping devices respectively, each 15 being arranged to control the release of the corresponding brush sets of all of said switches, an operator's sending device including a key set and a pair of registers arranged to respond to the operation of any 20 one of the keys in said set, and circuits for said magnets respectively closed at series contacts of both of said registers.

In witness whereof I hereunto subscribe my name this 13th day of January, A. D. 25
1916.

ALBEN E. LUNDELL.
